[57] CLAIM

The ornamental design for a knife handle, as shown.

DESCRIPTION

FIG. 1 is a front elevational view of a knife handle showing my new design;

FIG. 2 is a rear elevational view thereof;

FIG. 3 is a top plan view thereof;

FIG. 4 is a bottom plan view thereof;

FIG. 5 is a left side elevational view thereof; and,

FIG. 6 is a right side elevational view thereof.

The broken line showing of environment is for illustrative purposes only and forms no part of the claimed design.

FIG. 1.

FIG. 5.

FIG. 2.

FIG. 3.

FIG. 6.

FIG. 4.
